(57) **CLAIM**

The ornamental design for a muffin pan as shown and described.

DESCRIPTION

FIG. 1 is a top perspective view of a muffin pan according to the present invention.

FIG. 2 is a bottom perspective view of the muffin pan of FIG. 1.

FIG. 3 is a top plan view of the muffin pan of FIG. 1.

FIG. 4 is a bottom plan view of the muffin pan of FIG. 1.

FIG. 5 is a front elevational view of the muffin pan of FIG. 1.

FIG. 6 is a left elevational view of the muffin pan of FIG. 1.

FIG. 7 is a rear elevational view of the muffin pan of FIG. 1; and,

FIG. 8 is a right elevational view of the muffin pan of FIG. 1.

The broken lines in the figures show portions of the muffin pan and form no part of the claimed design.
